UNITED STATES PATENT OFFICE.

FRITZ GRÜNING, OF THUN, SWITZERLAND.

BLOCK-SIGNAL SYSTEM.

1,392,254.

Specification of Letters Patent. Patented Sept. 27, 1921.

Application filed February 3, 1921. Serial No. 442,290.

To all whom it may concern:

Be it known that I, FRITZ GRÜNING, a citizen of Switzerland, and residing at Thun, Canton of Berne, have invented certain new and useful Improvements in Block-Signal Systems, of which the following is a specification.

The present invention relates to a block signal system for preventing accidents on electrically worked rail roads where the 10 electric locomotive is attended by a single man.

This signal system comprises two circuit breakers of the line, the one connected with the distant or advance signal and the other connected with the home or main signal and both worked simultaneously with the signals by means of an interlocking frame worked from the depot. Said circuit breakers 15 when operated will interrupt the circuit of the line between the two signals. The arrangement comprises also at least one danger signal on the locomotive, the circuit of said signal being closed when the locomotive is running past the stop signal, thus 20 warning the engineer and causing him to operate the breakers. The arrangement further comprises a controlling clock work operating the hand of a dial whereof a certain 25 sector is provided with a contact sector with which the hand, acting as a contact lever, will make contact, say every minute and close the circuit of a siren so as to alarm the train staff in case the engineer be not 30 vigilant enough to operate a circuit breaker in order to prevent the sounding of the siren.

The system comprises also other auxiliary contrivances which will be set forth hereinafter.

The annexed drawing represents one working example of the invention adapted to a Swiss railroad.

Figure 1 is a longitudinal side elevation of a section of a line fitted up with the new signaling devices.

Fig. 2 is an elevation across the line.

Fig. 3 a diagrammatical view of the rigging working the circuit breakers and the 50 signals and

Fig. 4 a diagram of the electrical connections of the locomotive.

According to Figs. 1, 2 and 3 the overhead line outside of the signal section of a station comprises a contact wire 1 and a carrying wire 2 and ends at the cross beam 3 near to a semaphore signal 5 used as home signal and the cross beam 4 near to a disk signal 6 used as distant signal. The contact wire 1 of the lines outside of the two signals 60 is attached to insulators 7 and is separated from the line 9 between the two signals which is attached to insulators 8. Likewise the carrying wire 51 between the two signals is separated from the wire 2 outside of 65 the signals and is attached to the insulators 50 while the outside wire is suspended to insulators 49. Guide rails 10 are fixed to the cross beams 3 and 4, insulated therefrom and are arranged parallel to said wires in 70 such a manner that the bow-collector of the locomotive will freely pass over the space between the wire ends 1 and 9. Lever switches are provided on the cross beams 3, 4 carried by supports 11 and 12 and connected in such a way with the ends of the contact wires 1 and 9 that wire 1 is attached to insulated contact pieces 13 and wire 9 to insulated contact levers 14, connecting rods 15 attaching said levers to bell crank 75 levers 16 mounted at the top of the supports 12 and rods 17 connecting said bell crank levers to the middle arms of T-shaped levers 18 mounted at the bottom part of said supports, all in such a way that a similar position of the T levers 18 will answer to a corresponding similar position of the contact levers 14, such as shown in Fig. 1. The corresponding arms of the T levers 18 are connected by wire ropes 19. The lower 80 arm of the T lever 18 of the distant signal 6 is attached by a connecting rod 20 to one arm of a bell crank lever 21 mounted on the supporting mast of the signal, the other arm of which lever 21 being attached by a 85 hinged rod 22 to an arm 23 on the back side of the signal disk so as to keep this disk in its normal position of "stop." The lower arm of the T lever 18 of the home signal 5 is hinged by means of a connecting rod 90 24 to one of the cross arms of a T lever 25 mounted on the supporting mast 45 of the home signal 5, the other cross arm of said lever being attached to one end of a wire rope 28 running over the hand wheel 100 26 of a locking frame 27 worked from the depot or station and the middle arm of said T lever being attached to the other end of said rope. A connecting rod 29 hinged to the shorter arm of the home signal 5 is connected to a point between the 105 end of the middle arm of the T lever 25

and the pivot of such lever. The position as shown in Fig. 1 with cut-out contact levers and therefore with interrupted electrical connections on the line between the 5 two signals is the "stop" position and a turn of 90° given to hand wheel 26 will establish the position of "line clear" of the two signals. In this position contact levers 14 are making contact, the electrical connections of the overhead line are therefore 10 continuous, the disk of the distant signal will be in a horizontal position and the arm of the home signal in a vertical position.

The arrangement described above relates 15 to the provisions made on the line, Fig. 4 gives those made on the locomotive, only the necessary parts connected with the new arrangement being shown.

An optical signal comprising three red 20 lamps 30 connected in series is provided in the driver's cab.

These lamps are connected by a conductor 36 to the circuit of the electrical lighting system of the locomotive, as shown to the junction box 31, and to a contact piece 33 fixed at the zero point of the voltmeter 32 for high tension, which will make contact with the hand 34 whenever the voltage sinks under 10,000 volts and when the hand is falling back to zero. The hand of this voltmeter is connected to the circuit of the electric light at the junction box 31 by a conductor 35 provided with a circuit breaker 38 which will block up the pneumatic main switch, 30 not shown, in a manner, not shown, whenever the bow collector is in the pulled down position.

Besides this optical signal there is also an acoustic signal comprising an electric bell 40 39 shunted on the conductor 36 between the junction box 31 and the lamps and a hand worked switch 37 is provided in this shunt circuit.

A further signaling device at the driver's 45 cab comprises a controlling clock work 40 with a dial and a hand 41 making one complete turn every minute and acting as a contact lever which will make contact at every turn with an insulated contact strip 42 50 which is covering a sector of the dial, sector of a determined length say 20 seconds. This strip 42 is electrically connected to the junction box 31 and the hand 41 to an electrically worked siren 43, which is also connected to the contact piece 44 of a press switch, the press lever 45 of which is provided with a knob 48 and connected to the junction box 31. Lever 45 is kept in the cut out position by a spring 46 while a stop pin 55 60 47 of the lever 45 prevents any excessive compression of the spring 46.

A hand worked switch 53 is provided within the circuit between the junction box 31 and the contacts 44, 45 and has for its 65 object to lock an annular disk or limb 57 of

the controller of the locomotive in its A position or in its position of "line clear", as soon as the switch is in its cut out position, which position must be established when the locomotive is stopping.

The working example as shown in Fig. 4 comprises a tooth segment 55 fixed to the lever of switch 53 and engaged with a bolt provided with a rack 56. Limb 57 adapted to turn on a disk 59 having a pointer 58 is 70 fitted with a controlling handle 54 and with a notch into which the rack bolt 56 can be engaged when the "A" of the division on limb 57 agrees with the mark 58. By this arrangement the limb 57 can be locked in the 75 position of "A" that is in the position of "cut out" of the switch where also the circuit of the siren is cut out.

As regards the fact, that there is no current in the line wire, while the signals are 80 in their stop position, it must be mentioned, that all Swiss locomotives have an equipment of accumulators which being loaded by a dynamo driven by the wheels are connected to the junction box and will furnish the current and the current for operating auxiliary apparatus, whenever the line current is lacking. But whenever the line current is feeding again the locomotive, transformed current will be furnished for such 85 service from the line current.

The whole signal arrangement is operated as follows:

During the journey the controlling clock is switched on because the hand worked 100 switch 53 is closed whereby limb 57 with handle 54 has been imbolded. Every 40 seconds therefore contact would be made on the contact strip 42 and the siren 43 would be worked, which would alarm the train staff 105 for operating the brakes, if the engineer was not vigilant enough to depress knob 48 of the circuit breaker of the clockwork just before the hand 41 reached the contact strip. In this way the engineer is forced to be constantly vigilant, otherwise and in case of his incapacity for service the siren would be 110 heard and alarm the train staff.

Supposing that at the depot the distant signal 6 and the home signal 5 are set on 115 "stop" and the interval between both is cut from the circuit because levers 14 are in the cut out position, then, if the locomotive overruns the distant signal set on "stop" and travels on the cut out interval between 120 the signals, the high tension voltmeter 32 will at once show the zero. The circuit of the lamps 30 and the bell 39 will be closed and the lamps will be lit up and the bell be rung, thus notifying the engineer that he 125 has overrun the distant signal and advising him to work the necessary brakes or to have them worked at once.

If the locomotive comes to a stop on the line between the two signals it will not be 130

able to leave said section of the line again unless the signals have been opened again by the locking frames at the depot, that is, unless switch levers 14 have been closed and 5 the interval between the signals been again switched into the circuit. During the stop the engineer may stop the bell, as well as interrupt the circuit of the clockwork; but the lamps will continue burning. If the 10 lamps go out, it would indicate that the signals have now been put on "line clear." If the engineer wants to start the locomotive again the switch 53 must be cut-in in order to unbolt again limb 57 and handle 54 and 15 the circuit of the clockwork 40 will be closed again.

The clockwork may also be combined with a counter marking every complete revolution of the hand 41 on the dial but this only 20 during the running of the locomotive.

What I claim is:

1. In a signaling arrangement for preventing accidents on electrically operated rail roads where the electric locomotive is 25 attended by one man, and in combination, two circuit breakers 13, 14, the one connected with the usual distant or advance signal 6 and the other connected with the usual home or main signal 5, an interlocking plant adapted to transmit motion from 30 the usual locking frame located at the station to the circuit breakers, so as to operate the latter simultaneously with the signals, at least one danger signal actuated by a storage battery and controlled by a circuit closer 35 both situated upon the locomotive and adapted to warn the engine driver and provided on the locomotive with means for closing its circuit in case the locomotive has 40 overrun the stop signal, a danger signal upon the locomotive adapted to warn the train staff of the inattention of the engine driver, a clockwork for operating the danger signal for the train staff and a hand 45 operated circuit breaker for controlling the operating of the last said signal substantially as shown and described and for the purpose set forth.

2. In a signaling arrangement according 50 to claim 1 two danger signals adapted to

warn the engineer, the one acoustic and comprising a clockwork and the other an optical and comprising three red electric lamps for the purpose set forth.

3. In a signaling arrangement according 55 to claim 1 a danger signal adapted to warn the train staff comprising an electrical siren, a switch for controlling the current of said siren and comprising a dial 40, a contact sector 42 on said dial and a hand 41 worked 60 by a clockwork, all substantially as shown and described and for the purpose set forth.

4. In a signaling arrangement according 65 to claim 1, and in combination, a press switch, comprising a press lever 45, a spring 46 controlling the same, a contact piece 44, a press knob 48 and a stop pin 47 adapted to compel the engineer to be vigilant and to operate said switch every minute in order to prevent the sounding of the siren, all sub- 70 substantially as shown and described.

5. In a signaling arrangement according 75 to claim 1 and in combination a high tension volt meter of the current of the electric traction comprising a graduation 32, a hand 34 80 constituting the movable contact of a switch and a contact point 38 at the zero mark as a fixed contact of the switch for the purpose of closing the circuit when the high tension drops to zero all substantially as shown and described and for the purpose set forth.

6. In a signaling arrangement according 85 to claim 1, and in combination with a notch provided on the limb 57 of the switch of the locomotive of a hand worked switch 53 comprising a tooth segment 55 and a rack bolt 56 meshed with said segment for the purpose, when in the cut out position of the switch, of cutting out the siren, and of locking the limb in its "A" position or the position of "line clear," the whole substantially 90 as shown and described and to be operated when the locomotive is stopping.

In testimony whereof I hereby affix my signature in presence of two witnesses.

FRITZ GRÜNIG.
